CLAIM

U.S. PATENT DOCUMENTS

The ornamental design for a combined disc player and radio receiver, as shown and described.

D410,237 S * 5/1999 Kanatani D14/156
D421,752 S * 3/2000 Zeitman D14/156
D421,975 S * 3/2000 Steel D14/217
D426,538 S 6/2000 Deguchi
D436,094 S * 1/2001 Yamada D14/195

DESCRIPTION

FIG. 1 is a perspective view of a combined disc player and radio receiver showing my new design; and,

FIG. 2 is a front elevational view thereof.

Portions in broken lines are for illustrative purposes only and form no part of the claimed design.
